COMBING MACHINE FOR TEXTILE FIBERS

John William Nasmith, Heaton Mersey,
Manchester, EnglandApplication October 14, 1942, Serial No. 461,959½
In Great Britain June 26, 1941

4 Claims. (Cl. 19—116)

1

In textile combing machines of the Nasmith type, it is known to oscillate the top comb independently of the usual nipper which engages the fibre tuft being combed. This is effected by connecting the top comb arm to an arm or lever keyed upon a separate shaft—the top comb shaft—with means for oscillating or rocking the latter. The nipper shaft and the top comb shaft rock exactly in time as they should, but it is not necessary that they should have the same amplitude or extent of movement; it is indeed desirable that the amplitude or extent of throw of the top comb should be capable of variation to suit different types of fibres being dealt with. It is an object of the present invention to provide simple means whereby this variation can be effected when desired whilst preserving the synchronism of movement of the nipper and top comb and without altering the working position of the latter in relation to the detaching roller. A further object of the invention is to provide means whereby the amplitude or extent of throw of the top combs of all the heads of a combing machine may be altered simultaneously and to exactly the same degree.

According to the invention there is provided between the top comb shaft and the means for rocking the same a transmission rod one end of which is pivoted, the other end adjustably engaging upon a part associated with the top comb shaft or the rocking means therefor, as the case may be. Most conveniently the means for adjustable engagement consists of an arcuate slot in which engages a pin borne by the adjusting rod. Adjustment of the pin in the slot, with movement of the adjusting rod around its pivotal point which constitutes the centre of the arc, thus serves to vary the amplitude or extent of throw of the top combs by varying the extent of oscillation of the top comb shaft, without in any way affecting the working position of a top comb.

In Nasmith combing machines, two types are in industrial use, which may be differentiated broadly by stating that in one form the swinging machine nipper hinges upon a point below the combing machine cylinder; whilst in the other the nipper hinge point is above the said cylinder. This present invention is illustrated in the accompanying drawings with convenient mechanical arrangements by way of example as applied to each of these types of machine. In these drawings Figure 1 is a side elevation of mechanism as applied to the first mentioned type of Nasmith combing machine; Figure 2 is a sim-

2

ilar view of mechanism designed for application to the second named type; and Figure 3 illustrates a modified form of device of Figure 2. It will be understood that in either form of machine to which the invention is applied the mechanism of other parts of the machine not referred to herein may be of the usual or any type.

Referring first to Figure 1, the top comb arm is indicated at 3 and it is pivoted upon a pin 4 in the lever 5 keyed on the usual top comb shaft T. W indicates the nipper shaft of the machine, and there is provided the slide bar 6 having at one end thereof the upwardly curved extension 7 in which is formed the arcuate slot 8. Keyed on the top comb shaft T is the lever 9 and pivoting in one end of such lever is the swivel block 10 through which passes the rod 11 which serves as adjusting rod. The other end of this rod pivots upon a pin 12 which passes through the arcuate slot 8 and is movable therein, a clamping nut serving to clamp such pin in any position in such slot. The arc of slot 8 is struck from the pivot pin of the swivel 10 as centre when the top comb is in its most forward position. When the parts are in the position shown in the figure the top comb, operated from the top comb shaft T, is in its most forward position, and it will be obvious that the pin 12 can be adjusted in the slot in any position without in any way affecting the position of the top comb itself. Any increase or diminution of the amplitude of swing of the top comb is effected at the rear end of its movement where the comb is inoperative, but this increase or diminution of the amplitude of swing has a slight effect upon the distance the top comb travels during its operative or detaching period, which is the result desired. The rod 11 is provided with adjusting nuts 13 so that the shaft T and all the appended parts of the top comb can be adjusted simultaneously.

As will be understood, the mechanism described and illustrated is duplicated at the other side of the machine.

In Figure 2 of the drawings the parts shown for the carrying out of this invention are as those described with reference to Figure 1, the assembly being however varied to suit the type of combing machine in which they are employed. In this Figure 2 the top comb carrier is shown at 14; and the top comb shaft at T. The three-armed lever 15 is rocked about the pivot 16 as usual, and has pivoted upon its upper arm at 17 the end of link 18 the other end of which is pivoted upon the pin or stud 19 which engages as shown the arcuate slot 20 formed in lever 21, to be adjusted

in such slot as required and secured in adjusted position by a securing nut, the link 18 moving about pivot point 17 as centre, and from which centre the arc of slot 20 is struck. The lever 21 being keyed upon the top comb shaft T, this lever, link 18, and lever 15 constitute the means for rocking such shaft to an extent which is regulated by the adjustment of the pin or stud 19 in the slot 20. It follows from this, as in the form shown in Figure 1, that the drive may be adjusted without in any way affecting the position of the top comb 14 of any head of the machine during such adjustment, but the amplitude of throw or swing of the top comb will be varied according to the distance to which the pin or stud 19 is adjusted to or from the top comb shaft T. Upon this latter shaft is keyed the lever 22 to which is pivoted the end of the connecting rod 23 which carries the fork 24 engaging the pin 25 in the top comb carrier 14. The adjustable drive is thus transmitted to the top comb.

In Figure 3 is shown a form of mechanism in which, instead of employing the oscillated lever 15 of Figure 2, as the means for rocking the top comb shaft T, this operation is effected directly from the usual nipper operating shaft W. The latter has keyed upon it the lever 26 with arcuate slot 27, in which slot engages the pin or stud 28 upon which pivots the end of the link 29, a clamping nut being provided to secure the said pin or stud in adjusted position in the slot. The other extremity of the link is pivoted as shown upon the lever 30 keyed upon the top comb shaft T. As in the other modifications, the arc of the slot 27 is struck from the pivotal point upon lever 30 of the link 29 when the top comb carrier 14 of Figure 2 with its top comb is in the most forward position, and adjustment of the pin or stud 28 in the slot, to or from the nipper shaft W, effects the desired variation of the extent of the oscillation of the top comb shaft T transmitted from the oscillating nipper shaft W.

I claim:

1. In a textile combing machine, a movable top comb carrier, an oscillatable top comb driving shaft, transmission means between such shaft and the top comb carrier, oscillated driving means for the said shaft, a transmission rod pivoted between such driving means and the top comb shaft, and a lever mounted upon one of the oscillated members such lever having an arcuate slot therein, said slot extending substantially

radially in respect to the axis of said one oscillated member, with which slot one end of the transmission rod adjustably engages, the arc of such slot being struck from the point of connection of the transmission rod with the other oscillated member when the top comb is in its most forward position and such rod forming a radius from its pivotal point at all adjusted positions of its end within the slot.

2. In a textile combing machine, a movable top comb carrier, an oscillatable top comb shaft, a lever radial of such shaft, a slide bar constituting driving means for the shaft, an arcuate slot formed in such slide bar, and a transmission rod pivoted between the slot and the lever upon the top comb shaft and adjustable in such slot, the arc of the slot in the slide bar being struck from the pivotal point of the transmission rod upon the lever of the top comb shaft when the top comb is in its most forward position and such rod forming a radius from its pivotal point at all adjusted positions of its end within the slot.

3. In a textile combing machine, a movable top comb carrier, an oscillatable top comb driving shaft, driving means for the said shaft, a transmission rod pivoted between such driving means and the top comb shaft, a lever mounted radially upon the top comb shaft, such lever having an arcuate slot therein with which one end of the transmission rod adjustably engages, the arc of such slot being struck from the point of connection of the transmission rod with the driving means when the top comb is in its most forward position and such rod forming a radius from its pivotal point at all adjusted positions of its end within the slot.

4. Textile combing machine mechanism as claimed in claim 1, the slotted lever being mounted directly upon the nipper shaft of the machine.

JOHN WILLIAM NASMITH.
